(57) **CLAIM**

I claim the ornamental design for a slab, as shown and described.

DESCRIPTION

FIG. 1 is a perspective view of a slab showing my new design; FIG. 2 is a top view of the slab of FIG. 1; FIG. 3 is a front view of the slab of FIG. 1; FIG. 4 is a right side view of the slab of FIG. 1; FIG. 5 is a rear view of the slab of FIG. 1; FIG. 6 is a left side view of the slab of FIG. 1; and, FIG. 7 is a top view of the slab of FIG. 1 with its environment shown in broken lines.

The broken lines immediately adjacent the shaded areas represent the bounds of the claim, and all other broken lines are included for the purpose of illustrating portions of the slab that form no part of the claimed design. The broken line showing of the like slabs in FIG. 7 view represents the environmental subject matter. None of the broken lines form a part of the claimed design.
